US00D928183S

(12) **United States Design Patent** (10) **Patent No.:** **US D928,183 S**
(45) **Date of Patent:** **** Aug. 17, 2021**

(54) **DISPLAY PANEL OR PORTION THEREOF WITH A GRAPHICAL USER INTERFACE**

(71) Applicant: **MAGIC LEAP, INC.**, Plantation, FL (US)

(72) Inventors: **Lorena Pazmino**, Wilton Manors, FL (US); **Karen Stolzenberg**, Fort Lauderdale, FL (US); **Tim Zurmoehle**, Fort Lauderdale, FL (US); **Andrea Isabel Montoya**, Plantation, FL (US); **Gregory Minh Tran**, Miami, FL (US)

(73) Assignee: **Magic Leap, Inc.**, Plantation, FL (US)

(**) Term: **15 Years**

(21) Appl. No.: **29/740,150**

(22) Filed: **Jul. 1, 2020**

Related U.S. Application Data

(62) Division of application No. 29/640,729, filed on Mar. 16, 2018, now Pat. No. Des. 892,131.

(57) **CLAIM**

The ornamental design for a display panel or portion thereof with a graphical user interface, as shown and described.

DESCRIPTION

FIG. 1 is a front view of a display panel or portion thereof with a graphical user interface showing a first embodiment of our design; and.

FIG. 2 is a front view of a display panel or portion thereof with a graphical user interface showing a second embodiment thereof.

The outmost broken line rectangle illustrates a display panel or portion thereof that forms no part of the design. The reaming broken lines, including all text, illustrate portions of the graphical user interface or mixed reality environment and form no part of the claimed design.

1 Claim, 2 Drawing Sheets
